DESIGN FOR A SACHET POMPON CAT

Alex Fine, St. Paul, Minn., assignor to Stuart Inc.,
St. Paul, Minn., a corporation of Minnesota

Application May 15, 1948, Serial No. 146,400

Term of patent 14 years

(Cl. D86—10)

To all whom it may concern:

Be it known that I, Alex Fine, a citizen of the United States of America, residing at St. Paul, in the county of Ramsey and State of Minnesota, have invented a new, original, and ornamental Design for a Sachet Pompon Cat, of which the following is a specification, reference being had to the accompanying drawing, forming part thereof.

Fig. 1 is a side elevation of a sachet pompon cat showing my new design;

Fig. 2 is a front elevation of the sachet pompon cat shown in Fig. 1, showing the fore parts thereof; and,

Fig. 3 is a top plan view of the sachet pompon cat shown in Fig. 1.

The characteristic features of my design reside in the combination of the specific animal body shown with contiguously positioned front paws underneath the head and in the plano ears positioned transversely on the head in front of and at an angle to a vertical line through the center of the head, as shown.

I claim:

The ornamental design for a sachet pompon cat, as shown and described.

ALEX FINE.
